UNITED STATES PATENT OFFICE

139,232

DESIGN FOR A BEVERAGE DISPENSER

Hari C. Timmis, Kendallville, Ind., assignor to McCray Refrigerator Company, Kendallville,
Ind., a corporation of Indiana

Application August 1, 1944, Serial No. 114,674

Term of patent 7 years

(Cl. D2—3)

To all whom it may concern:

Be it known that I, Hari C. Timmis, a citizen of the United States and resident of Kendallville, in the county of Noble and State of Indiana, have invented a new, original, and ornamental Design for a Beverage Dispenser, of which the following is a specification, reference being had to the accompanying drawing, forming a part thereof.

In the drawing, Fig. 1 is a rear perspective view of a beverage dispenser, showing my new design, and Fig. 2 is a front perspective view thereof.

The dominant features of the design reside in the portions shown in full lines.

I claim:

The ornamental design for a beverage dispenser, substantially as shown and described.

HARI C. TIMMIS.
